UNITED STATES PATENT OFFICE.

MILLARD P. OSBOURN AND EDWARD W. COMFORT, OF MERCHANTVILLE, NEW JERSEY,
ASSIGNORS TO WARREN WEBSTER & COMPANY, A CORPORATION OF NEW JERSEY.

LOW-TENSION STEAM-HEATING SYSTEM.

1,096,941.

Specification of Letters Patent.

Patented May 19, 1914.

Application filed September 13, 1907. Serial No. 392,624.

To all whom it may concern:

Be it known that we, MILLARD P. OSBOURN and EDWARD W. COMFORT, of the city of Merchantville, county of Camden, and State 5 of New Jersey, have invented an Improvement in Low-Tension Steam-Heating Systems, of which the following is a specification.

Our invention has reference to low tension steam-heating systems, and consists of certain improvements which are fully set forth in the following specification and shown in the accompanying drawings, which form a part thereof.

Our invention has for its object the regulation or control of means for varying the pressure of the steam in the steam main from which the heating system derives its heat energy.

More specifically, our improvement comprehends the regulation of a valve that controls the extent of vacuum which is permitted to exist in the exhaust pipe or main of a steam engine and from which the steam 25 is supplied to the heaters or radiators.

Our invention consists of an automatic regulator of special construction adapted for use in a low pressure system of steam heating such as disclosed in application Ser. No. 30 312,080, filed April 17, 1906, in the name of Millard P. Osbourn, one of the applicants of this application.

More specifically, the invention consists of a relief valve to control the pressure operating the diaphragm valve which regulates the extent of vacuum in the exhaust main, combined with a lever device for normally holding the relief valve more or less closed, an expansible bellows for operating 40 the lever device to open the relief valve, and one or more thermostatic devices for controlling the operation of the bellows.

Our invention also comprehends details of construction which, together with the features above specified, will be better understood by reference to the drawings, in which:

Figure 1 is a diagram illustrating a low tension steam-heating system having our invention applied thereto; Fig. 2 is an elevation of our improved regulator; and Fig. 3 is a plan view of the same.

Referring to the system illustrated in Fig. 1, we have a valve in the exhaust or 55 suction to the condenser which constitutes

the means for the regulation of the steam pressure in the steam main or exhaust pipe.

B represents an engine exhausting at B' into a main exhaust pipe C, one branch of which supplies the steam heating system and is provided with the usual escape pipe D to the atmosphere to permit excess of exhaust steam to escape, and another branch C' which leads to the condenser G.

The radiators or heating units of the heating system are indicated at A and these communicate with the main supply pipe C by a suitable pipe or riser A' and discharge through a return pipe E' to the main return main E which leads to the condenser. 70 A suitable valve F—automatic or static—may be arranged in the return E' to control the discharge from the radiator or heat unit.

J is an automatically operating valve in the exhaust connection to the condenser, the regulation of which controls the suction or partial vacuum produced by the condenser upon the exhaust pipe and engine. This valve is automatically regulated 75 by thermostatic devices, controlled by the temperature exterior to the building and preferably also by the temperature of the steam supply to the heating system. In the drawings, we have shown the valve J operated by compressed air which is adapted 80 to act upon the diaphragm through a pipe K leading from a reservoir L' in which compressed air is delivered by a compressor L; and this valve J is controlled by a regulator 85 M operated thermostatically by the outside thermostat N and, if desired, also by the steam temperature thermostat O which is contained within the exhaust pipe.

A pipe K' leads from the air chamber of the diaphragm valve J, and its end D' is controlled by a relief valve t which is controlled by the regulator M thermostatically operated. When the relief valve t is open, the diaphragm valve J will open to a greater 100 extent, thereby permitting the vacuum in the condenser to be exerted in the exhaust pipe to lower its pressure and consequently reduce the tension of the steam which is supplied to the heating system, this regulation being automatically performed to meet the conditions indicated by the thermostatic devices.

The thermostats N and O are adapted to operate with an expansible fluid, and this

expansible fluid we prefer shall be air under low pressure of about $1\frac{1}{2}$ pounds per square inch at 70° temperature. These two thermostats are united as at n and by means of a pipe o they communicate with the interior of the expansible bellows u , which may consist of a series of annular chambered parts u^2 connected at their central parts by ring portions u^3 so as to have capacity to expand and contract. By this arrangement, the action of the two thermostats is such that they both coöperate at all times in producing a resultant action upon the regulator M for the diaphragm valve J . It is, of course, evident that either one of these thermostats might be omitted if desired.

Air is preferred to be used in the thermostats because it responds to changes of temperature much more readily than liquids; its rate of expansion is the same at any temperature; and the difficulty of keeping the thermostats absolutely full of liquid is obviated. Therefore, while we prefer the use of air we do not confine ourselves thereto as any gas or liquid may be used, if so desired.

The bellows u has one end rigidly connected to the frame of the regulator and through which the air from the thermostats pass and has the other or free end connected to a lever a which is adapted to be depressed by the expansion of the bellows. The lever a is fulcrumed upon a spring plate a' , and its free end is connected by a link c with a second lever b , which latter is fulcrumed at b' on one side of the link and is connected at the other end with the relief valve t . The link c is adapted to notches in the levers so as to retain any position of adjustment which may be given to it, the said adjustment being adapted to vary the throw of the lever b with any given movement of the lever a under the action of the bellows u . Arranged below the lever a and in line with the bellows u there is provided a spring m which presses upward against the levers in opposition to the thermostatic bellows u and furnishes the force necessary to close the valve t .

The valve t is in effect the outlet to the diaphragm chamber of the valve J , and it is evident that, if the outlet valve t be practically closed, air will slowly pass the nearly closed valve while accumulating pressure back of the diaphragm valve, and more or less closing the same. The valve t has considerable area and the pressure that can accumulate behind the diaphragm valve J depends upon the amount of the spring m pressure exerted to hold the valve t closed modified by the thermostatic pressure. This pressure for closing the valve t varies with the action of the thermostats in the following manner: The expansion of air in the thermostats acting through the bellows u

will weaken the pressure of the spring m , and the accumulated air pressure back of the valve t will then open the said valve and keep it more or less open until all of the pressures exerted on the valve t to close it balance the pressure which opens it. This action to be accurate would necessitate that the atmospheric pressure be constant, but it is not, and consequently by substituting elastic air for the inelastic non-compressible liquids, the apparatus becomes very susceptible to barometrical influences. These changes, however, may be accurately compensated for by inclosing the spring m in a hermetically sealed bellows u' of the exact size and shape of the thermostatic bellows u . As these bellows are placed opposite to each other, it is evident that all changes in atmospheric pressures become neutralized. This inclosing bellows u' is shown in section to expose the spring m within it. One end of the bellows is secured to the abutment for the spring while the other end of both the spring and bellows are connected and move with the lever a .

A U-shaped glass tube S is shown back of the levers and to one side of the bellows and is adapted to contain mercury so as to constitute a gage to indicate thermostatic pressure on the bellows, the upper end of the tube being in communication with the tube from the thermostats leading to the bellows. There is also shown a pressure gage T which is in communication with the pipe leading from the diaphragm valve, and therefore indicates the pressure of the air between said diaphragm valve and the relief valve t .

The adjustable link between the levers a and b permit the change of leverage of the lever device which actuates the valve t , and consequently, the pressure which keeps the valve t closed against the action of the compressed air may be adjusted to operate on any desired change in temperature.

Our invention covered in this application has particular reference to the special construction of the regulator M as a whole, and also to the same in connection with the means for operating the diaphragm valve of the condenser.

While we have shown our improvement in connection with one form of apparatus designed to operate on low tension, it is understood that any low tension system in which the tension of the steam is dependent upon the operativeness of a regulated valve device is comprehended by our invention.

Broadly considered, our invention is adapted for use in connection with means for thermostatically controlling the circulation of steam irrespective of the particular industrial purpose for which the circulation is effected. Moreover, it is applicable to any system where the temperature and pressure of

the steam is required to be regulated under thermostatic control, whether the said thermostatic control be dependent upon the external atmosphere or upon the temperature or pressure within the pipe or chamber directly or indirectly heated by the steam which is controlled. Our invention is also applicable to condensing plants for the purpose of controlling the partial vacuum produced by the condenser by temperature changes, such, for example, as variations in the temperature of the cooling water or changes in the outside temperature. While our invention is applicable for these various purposes, it is particularly adapted to steam heating systems where variations in the main steam supply are desirable to suit changes in climatic conditions, and is especially useful in the combination of a steam heating system with a condensing plant to enable a portion of the steam to be economically used for heating purposes without disproportionate loss in the condensing effects. While we prefer the construction shown as being excellently adapted for the purposes of our invention, we do not restrict ourselves to the details as they may be modified without departing from the spirit of the invention.

Having now described our invention, what we claim as new, and desire to secure by Letters Patent, is:—

1. Thermostatically operated controlling means consisting of a pressure controlling valve, a spring to close the said valve, thermostatically operated power devices consisting of a bellows containing a fluid under pressure to oppose the action of the spring to open the valve, a thermostat for changing

the pressure of the fluid to vary the power of the thermostatically operated bellows, and a second bellows of similar form inclosing the spring whereby the regulator is not affected by barometrical changes.

2. Thermostatically operated controlling means consisting of a movable member, a spring to move the movable member in one direction, a bellows comprising a series of connected annular chambered parts for moving the movable member in the other direction in opposition to the spring, a thermostatic device for supplying the bellows with an expanding medium to give it action, and a second bellows similar to the first-mentioned bellows in size and shape inclosing the spring and coöperating with it in operating the movable member in opposition to the first-mentioned bellows.

3. The combination of a controlling valve, a fluid-pressure-motor for controlling said valve, a vent from said fluid-pressure-motor, a valve controlling said vent, a lever for actuating said valve, a second lever, an adjustable connection between said levers, a spring to actuate said second lever and tending to close the vent controlling valve, power devices opposing the action of said spring and tending to open the valve, and a thermostat controlling the pressure to said power devices.

In testimony of which invention, we have hereunto set our hands.

MILLARD P. OSBOURN.
EDWARD W. COMFORT.
